SPOOL OR REEL

Maphet J. Young, Youngstown, Ohio

Application June 30, 1941, Serial No. 400,528

9 Claims. (Cl. 242—96)

This invention relates to an improved construction for a reel or spool and to an improved method of constructing the reel or spool.

The primary object of the invention is the provision of an improved construction for a spool or reel which construction enables substantial economies to be effected in the production of the spools or reels, particularly in large quantities. The article of the invention is adapted for general uses as, for example, the containing of tape, wire, conductor cord, clothes line and various other materials and, as will be pointed out hereinafter, possesses certain desirable advantages in widely varying fields of use.

A more specific object of the invention is the provision of an improved spool or reel which may readily and economically be produced from sheet metal or other suitable sheet material. To this end, the construction of the article is such that but two pre-formed elements are necessary for the complete assembly of the article, while each of the elements is identical and capable of being pre-formed by a simple pressing operation thereby materially reducing the die and fabricating costs attendant the production of the article.

Yet another object of the invention is the provision of an improved reel or spool which may be economically fabricated or assembled in varying capacities. This is accomplished in accordance with the preferred embodiment of the invention by so constructing the article that but a single pair of identical pre-formed parts are required to complete the article and by securing the parts in different relative positions with respect to each other, the capacity of the spool or reel may be varied.

A still further object of the invention is the provision of an improved arrangement for engaging the end of tape, wire, conductor cord, clothes line or other linear material, which arrangement may readily be incorporated in a spool or reel for containing such linear material during the primary construction of the spool or reel.

Other objects and advantages of the invention will become apparent as the exposition of the same proceeds and for the purpose of more fully disclosing my invention, a representative and preferred embodiment which is illustrated in the accompanying drawings will be described. It should be understood, however, that the invention is not limited to the particular structure or use shown in the drawings but is capable of various modifications.

In the drawings:

Figures 1 and 2 are side and front views, respectively, of a reel or spool constructed in accordance with the principles of the invention;

5 Figures 3 and 4 are front and inside views, respectively, of one of the two identical parts which make up the article of Figures 1 and 2;

Figure 5 is a sectional view along the line V—V of Figure 2;

Figure 6 illustrates a representative use to which the article of Figures 1 and 2 may be put;

Figures 7 and 8 are side and end views, respectively, of a modified form of the two parts which make up the reel or spool of the invention;

15 Figure 9 is a fragmentary view of a further modified form or part, the modification thereof pertaining to the shape and disposition of the means employed to secure the end of the line or wire;

Figure 10 is a view similar to Figure 6 but showing the modified form of reel; and

Figure 11 is an enlarged side view of the supporting handle of the reel of Figure 10.

The reel or spool in its preferred and illustrated embodiments is constructed of two identical sheet metal parts 10 and 11, each of which is provided with a circular edge 12 rolled over at 13 to provide a smooth outer edge in a manner well understood in the art. The drum of the reel 25 is formed of a plurality of circumferentially spaced struts or bars 14 which span the spaced parallel disk-like portions 15 of the members 10 and 11. Struts 14 are composed of projections 16 which extend laterally outward of one face 30 of the members 10 and 11 and which are integral with the portions 15 of the parts 10 and 11. Any number of struts may be employed in any of the modifications, depending on the size of the reel and the carrying capacity required.

35 Projections 16 are provided by cutting the metal of the disks 15 along the lines 17, 18 and 19 and bending the metal laterally of the plane of the disk along the lines 20, which lines are preferably concentric and equidistant from the center of the disk. To assemble the reel or spool, the projections 16 of the two identical parts 10 and 11 are overlapped, as indicated in Figure 5, and secured together by any suitable expedient, preferably by welding. The extent of overlap 40 between the projections 16 determines the interval between the two side disks 15 of the reel or spool and, consequently, the carrying capacity of the reel or spool. If it is desired to construct a narrow spool, the projections 16 of one disk 15 extend across to the other of the disks 15 and

vice versa. If a wide spool is desired, the projections 16 are overlapped to an extent only sufficient to enable the projections to be rigidly secured together. The circular nature of the projections 16 together with their circumferential disposition results in a box-like structure which possesses ample strength and rigidity for all purposes to which the spool or reel is normally put.

To provide means to secure and retain an end of the wire, line or other material to be coiled on the spool or reel, one of the lines of cut 17 on each of the disks 15 is provided with a saw tooth or other irregular outline, as indicated at 21 in Figure 1, so that when the adjacent projection 16 is bent out of the plane of the disk, the same will be provided with a laterally extending projection 22 in which is incorporated a laterally directed slot 23. The metal of projection 22 on either side of the slot 23 constitutes projections 24 over which a looped end of the wire, cord or other material may be pressed to hold the material at the beginning of the winding thereof. A knotted end of the material may be positioned inwardly of the slot 23 to hold the material at the beginning of the coiling thereof. It is also contemplated that the slot 23 may be wedge-shaped so that the material may be wedged therein and so held without requiring a loop or a knot at its end. It should be noted that the whole of the projection 22 extends laterally outward of the general side edge of the projection 16 on which it is positioned so that when this particular projection 16 is mated with a straight projection 16 of the other reel part in assembling the reel, the slot 23 and projections 24 will remain operative in the manner indicated above. The material of the projection 22 lies in the cylindrical plane of the projections 16. Since both of the parts 10 and 11 of the reel or spool are identical, each will be provided with one of the cord retaining projections 22 which projections will extend in opposite circumferential direction so that regardless of how the reel or spool is manually or machine held, the linear material to be coiled thereon may have its end readily secured to the drum of the reel or spool.

The part 10 (or 11) of the article is preferably produced by a stamping press, the dies of which may be either separated into blanking and bending stages or compounded for single cycle operation. In either case, the part may be made at low cost and at a high rate of production. To assemble the two parts of the reel or spool, it is contemplated that a specially designed welding jig will be employed to facilitate the welding together of the projections 16 and to enable this operation to be accomplished at high production speeds. Simultaneously with the blanking out of disks 15, a center aperture 25 is provided in the disk, which apertures may subsequently be employed to receive a supporting axle for the reel or spool. Also simultaneously, apertures 26 may be provided in the disk 15 within the circle of the lines 20 but outwardly of the center apertures 25. These latter apertures 26 may be employed for ventilating purposes in a manner more fully explained in my co-pending application Serial No. 300,569 filed October 21, 1939, now U. S. Patent No. 2,268,996, for clothes line reel.

Referring now to Figure 6 which illustrates a representative use to which the reel or spool of the present invention may be put, the article is shown as being provided with a supporting axle 30 provided at its outer end with a hook 31 and intermediate the hook 31 and the adjacent disk

15 is a handle 32 rotatably mounted on the axle. Eccentrically mounted on the other of the disks 15 is a handle 33 which in cooperation with the handle 32 may be employed to coil clothes line 34 onto the drum of the reel. It should be understood that by reason of the fact that the drum of the reel or spool provided by the projections 16 is of open construction and of the fact that the disks 15 are provided with ventilating apertures both inwardly and outwardly of the hollow drum, the coil of clothes line contained on the reel will be well ventilated both about its inner and outer surfaces and the ventilation will be facilitated by supporting the reel in a depending position with its axis substantially vertical, as illustrated in Figure 6.

Referring to Figures 7 and 8 which illustrate a modified form of the reel or spool part, it will be observed that the projections 161 which correspond in general to the projections 16 of Figures 3 and 4 are of uniform cross section and that alternate means as the key-hole aperture 162 in the face of the disk 12 is provided to anchor the knotted or looped end of the line, wire or other material coil on the reel. Aperture 162 consists of an enlarged part 163 from which extends a wedge-shaped recess 164. In use the knotted or looped end of the line may be passed through the enlarged part 163 and by moving the end of the line laterally into the recess 164, the same may be securely anchored to the side of the reel.

Figure 9 illustrates a modified form of aperture being designated by reference numeral 165, which aperture consists of an enlarged portion 166, a radially inwardly extending wedge-shaped recess 167 and circumferentially extending wedge-shaped recesses 168. While certain advantages accrue from the use of two identical parts in fabricating the reel as explained above, it should be apparent that the invention may be practiced by employing the notched-out feature in either modification in but one of the two parts making up the reel.

Figure 10 illustrates a representative use of a modified reel and shows a knotted end 134 of the clothes line 34 as being positioned on the outside face of the disk 12 at the aperture 162 or 165. A modified form of supporting handle 132 is shown, a side view of which appears in larger scale in Figure 11. As shown, handle 132 is provided with inwardly and upwardly directed transverse slot 133 providing, in effect, an integral hook which may be applied over the line 34 as indicated. Handle 132 is rigidly attached to the projecting end of a rod 135 which forms an axle about which the reel may be rotated by the handle 131.

The above specifically illustrated and described embodiments and use of the invention should be considered as illustrative only as obviously many changes may be made therein without departing from the spirit or scope of the invention. It is, for example, contemplated that the reel or spool of the invention may be fabricated from non-metallic sheet material as well as from metallic sheet material in which case, the projections 16 may be riveted or stapled or otherwise suitably secured together. When used as a display reel for strip or linear material, the plane surfaces on the outer sides of the disks 15 and intermediate the openings within lines 17-20 may be employed for ornamentation or advertising purposes. It should also be apparent that in the embodiment illustrated in Figures 1 through

6, the end of the line or wire may obviously be as readily attached to one or the other of the disks 12 at 21 as to the struts 14 at 23. Various other advantages and uses of the article of the invention are readily apparent. Reference should therefore be had to the appended claims in determining the scope of the invention.

What I claim is:

1. A reel or spool comprising in combination a pair of side members adapted to confine the side edges of a coil of wire and the like, said side members being formed of sheet-like material, a drum spanning said side members, said drum being constructed of overlapped and axially aligned tongues or projections pressed out of the material of said side members and bent inwardly toward each other, said overlapped projections or tongues being rigidly secured together, said projections or tongues being formed of the material of said side members radially outward of said drum, and axially aligned apertures in said side members adapted to receive an axle or rod to rotatably support said reel or spool.

2. An article according to claim 1 further including ventilating apertures in said side members radially intermediate said apertures and said drum.

3. An article according to claim 1 further characterized in that one of the side edges of one of said tongues or projections is contoured to provide as an integral part of said drum a circumferentially extending means to engage and retain an end of the wire and the like of the coil, said contoured side edge being cut out of the sheet-like material of one of said side members.

4. A reel or spool constructed of two identical stamped metal parts comprising in combination two identical sheet metal disks each having a plurality of drum forming tongues cut out from the material of the same and being bent at lines concentric about and equidistant from the geometric center of the same to extend laterally of the plane of the disk, the drum forming tongues of the two disks being aligned and overlapped a desired extent to form the drum, said overlapped tongues being welded or otherwise rigidly secured together, said projections or tongues being formed of the material of said side members radially outward of said drum, and axially aligned apertures in said side members adapted to receive an axle or rod to rotatably support said reel or spool.

5. An article according to claim 4 further including a laterally extending projection on one of the tongues of each of said disks, said laterally extending projections adapted to engage and retain an end of a wire and the like to be coiled on said article.

6. An article according to claim 4 further characterized in that one of the side edges of one of the tongues of each of said identical parts is provided with a projection which, when the parts are assembled, extends circumferentially of the

5 drum strut formed in part by the said tongue, the arrangement being such that the two projections provided by the two identical parts form two oppositely directed circumferentially extending wire or cord retaining means whereby an end of a wire and the like may be readily fastened to the reel regardless of the direction of rotation of the same.

7. A reel or spool comprising in combination a 10 pair of side members adapted to confine the side edges of a coil of wire and the like, a drum spanning said side members and formed of circumferentially spaced struts formed of interconnected tongues pressed out of the material of the side 15 members radially outward of said drum, one of the side edges of one of the tongues being contoured to provide a portion extending circumferentially of one of said struts thus providing means to engage and retain an end of the wire and the 20 like of the coil said contoured edge being cut out of the material of one of said side members whereby the slot remaining in said member is complementarily contoured along one of its side edges.

8. A reel for a clothes-line and the like comprising in combination a pair of side members 25 adapted to confine the side edges of a coil of said line and the like, said side members being formed of sheet-like material and having integral inwardly extending and axially aligned projections 30 or tongues pressed out of the material of the side members and connected together to form a drum, said projections or tongues being formed of the material of said side members radially outward of said drum, axially aligned apertures in said 35 side members centrally of said tongues or projections, a rod rotatably supporting the reel received in said apertures, a handle secured to said rod comprising a member having a hand grip portion, and an L-shaped slot in said portion providing a hook whereby said reel may be readily suspended from a strung line.

9. A reel or spool for a clothes line and the like comprising in combination a pair of side members formed of sheet-like material adapted 45 to confine the side edges of a coil of clothes line and the like, a drum spanning said side members on which the coil may be wound, an aperture in one of said side members radially outward of said drum; said aperture being provided with an enlarged portion, a wedge-shaped portion extending radially inward from said enlarged portion, and a wedge-shaped portion extending circumferentially from said enlarged portion, the arrangement being such that the forward end of a clothes 50 line and the like may be wedged in the first mentioned wedge-shaped portion at the start of a coiling operation and the outer end of the line and the like may be wedged in said second mentioned wedge-shaped portion at the end of the coiling operation.

MAPHET J. YOUNG.
